US00D940562S

(12) **United States Design Patent** (10) Patent No.: **US D940,562 S**
(45) Date of Patent: **** Jan. 11, 2022**

(54) **BEVERAGE BOTTLE**

- (71) Applicant: **F&I Beverages AG**, Zug (CH)
(72) Inventor: **Dmitriy Ignatenko**, Chisinau (MD)
(**) Term: **15 Years**
(21) Appl. No.: **35/509,236**
(22) Filed: **Mar. 26, 2020**

(80) **Hague Agreement Data**

- Int. Filing Date: **Mar. 26, 2020**
Int. Reg. No.: **DM/207402**
Int. Reg. Date: **Mar. 26, 2020**
Int. Reg. Pub. Date: **May 1, 2020**

(30) **Foreign Application Priority Data**
